(57) **CLAIM**

The ornamental design for a LED lens, as shown and described.

DESCRIPTION

FIG. 1 is a perspective view of a LED lens showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded perspective view thereof showing that the LED lens is mounted in a lighting device; and,

FIG. 9 is another exploded perspective view thereof in FIG. 8.

The broken lines depict environmental subject matter, are for illustration only and form no part of the claimed design.
